UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SPRING UNIT FOR DRAFT-RIGGINGS.

1,226,244.

Specification of Letters Patent. Patented May 15, 1917.

Application filed October 18, 1915. Serial No. 56,426.

To all whom it may concern:

Be it known that I, JOHN F. O'CONNOR, a citizen of the United States, residing at Chicago, in the county of Cook and State of Illinois, have invented a certain new and useful Improvement in Friction Spring Units for Draft-Riggings, of which the following is a full, clear, concise, and exact description, reference being had to the accompanying drawings, forming a part of this specification.

This invention relates to improvements in friction spring units for draft riggings.

An object of the invention is to provide a unit for railway draft riggings which is particularly adapted to replace the ordinary springs now used in tandem gears to thereby obtain a higher capacity.

Another object of the invention is to provide a shock absorbing member wherein are employed a plurality of plate springs which are confined between and supported by followers, the followers and springs having associated therewith friction means arranged to flex the plate springs against portions of the followers.

In the drawing forming a part of this specification, Figure 1 is a longitudinal, vertical sectional view of draft rigging showing my improvements in connection therewith. Fig. 2 is a horizontal sectional view taken substantially on the line 2—2 of Fig. 1. Fig. 3 is a vertical, transverse sectional view taken substantially on the line 3—3 of Fig. 1. Figs. 4, 5 and 6 are detail perspective views of a follower, shoe and wedge, respectively, employed in my invention.

In said drawing, 10—10 denote draft sills to which are attached stop members 11—11 having the usual front and rear end stops, front and rear intermediate stops and limiting stops for a tandem gear. The draw-bar 12 has connected therewith a yoke 13 of the usual tandem gear type, and mounted within each pocket of the tandem yoke is my improved unit, hereinafter described. The followers are guided and supported by straps 14—14 and transversely extending tie plates 15 are employed, all of any well known or desired construction.

Each of the improved units, which I have designated generally by the reference A, consists of two followers 16 and 17, each having on its inner face an inwardly extending, hollow, box-like projection 18, the

side-walls 19 of which are straight and the upper and lower interior walls 20—20 thereof are concaved. Mounted between the followers 16 and 17 are two sets of spring plates 21—21, an upper and a lower set, each set consisting of any desired number of plates to produce the requisite capacity, said sets of spring plates being shorter than the normal distance between the interior end walls of the followers 16 and 17. Interposed between the sets of spring plates 21 are a pair of friction shoes 22—22, each of said shoes having an outer convex surface 23 and an inner flat face 24, the flat faces being normally in engagement, as clearly indicated in Figs. 1 and 3. At their ends, the shoes 22 are provided with beveled or wedge faces 25 with which coöperate wedges 26—26 detachably carried by the followers 16 and 17, the wedges 26 being held in proper position preferably by means of studs 27 which engage in suitable holes 28 in the followers.

In operation, upon relative approach of the followers 16 and 17 of each unit, the approaching movement of the wedges 26 will force the shoes 22 apart in an up and down direction. Thereupon, the sets of spring plates 21 will be flexed in planes perpendicular to the axis of the gear, the upper set of spring plates being convexed upwardly between the upper surfaces 20 of the followers and surface 23 of the upper shoe 22, and the lower set of spring plates 21 will be flexed downwardly between the convex surface 23 of the lower shoe and lower surfaces 20 of the followers. The spring plates of each set are held in proper assembled position by any suitable means such as the rivets 29, and the shoes 22 and upper and lower surfaces 20—20 of the followers are suitably recessed to accommodate the ends of the rivets.

From the preceding description, it will be seen that I have provided a unit, which combines within itself spring and friction acting elements compactly arranged, and the capacity of each unit may be made relatively great on account of the number of spring plates which may be employed.

I claim:

1. A shock absorbing device for draft riggings which comprises, a pair of followers having hollow extensions on their inner opposite faces, said extensions having the inner walls parallel to the axis of the device curved, sets of plate springs interposed be-

tween said followers and mounted within said recesses, and means for flexing said sets of plate springs transversely against said curved walls upon relative approach of the 5 followers.

2. A shock absorbing device for draft riggings which comprises, a pair of followers having hollow extensions on their inner opposite faces, said extensions having curved 10 inner walls, sets of plate springs interposed between said followers and mounted within said recesses, and means for flexing said sets of plate springs against said curved walls upon relative approach of the followers, said 15 means including wedges carried by the followers and friction shoes coöperating therewith.

3. In a device of the character described, the combination with a pair of relatively

movable followers, each of said followers 20 having a recess on its inner face, opposite walls of said recesses being curved, of two sets of plate springs extending longitudinally between said followers and supported thereby, said plate springs normally bearing 25 against said curved surfaces, and wedges carried by the inner faces of said followers and adapted to enter between said sets of springs, whereby, upon relative approach of said followers, the plate springs are flexed 30 in a direction transverse to the line of movement of said followers against said curved faces.

In witness that I claim the foregoing I have hereunto subscribed my name this 29th 35 day of Sept., 1915.

JOHN F. O'CONNOR.
